BRIM POUNCING MACHINE

Burling D. Wells, Danbury, Conn., assignor to
The Mallory Hat Company, Danbury, Conn.,
a corporation of Connecticut

Application June 11, 1935, Serial No. 25,984

9 Claims. (Cl. 223—20)

This invention relates to a machine for pouncing a hat and more particularly to a hat brim pouncing machine.

One of the objects of this invention is to provide a hat brim pouncing machine which is simple and inexpensive in construction and thoroughly efficient and practical in operation. Another object is to provide a machine of the above nature which may be inexpensively operated without any great degree of skill. Another object is to provide a construction of the above nature which rapidly and thoroughly pounces the brim of a hat leaving the surface clean and free of the abraded fur particles. Another object is to provide a machine of the above nature which can readily accommodate hats, the brims of which vary in width and thickness. Another object is to provide a machine of the above nature which is conducive to the health of the operator and which may be operated without danger of injury. Another object is to provide a machine of the above nature in which the hat brim is uniformly fed during the pouncing thereof. Another object is to provide a machine of the above nature which is thoroughly reliable and durable under conditions of rigorous use. Other objects will be in part apparent and in part pointed out hereinafter.

The invention accordingly consists in the features of construction, combinations of elements, and arrangements of parts, as will be exemplified in the structure to be hereinafter described and the scope of the application of which will be indicated in the following claims.

In the accompanying drawing, in which is shown one of the various possible embodiments of this invention,

Figure 1 is a vertical elevation of my brim pouncing machine, certain parts thereof being broken away and certain parts thereof being shown in section;

Figure 2 is a diagrammatic front elevation of certain parts of my machine;

Figure 3 is a sectional elevation taken along the line 3—3 of Figure 2, and

Figure 4 is a horizontal section taken along the line 4—4 of Figure 1.

Similar reference characters refer to similar parts throughout the several views of the drawing.

As conducive to a clearer understanding of certain features of this invention, several of the shortcomings of apparatus designed for the same general use will be described. Many of the machines now in use feed the brim of the hat

through the pouncing rolls much too rapidly and accordingly the hat must be held back manually until the pouncer can complete this operation on the various portions of the brim. Thus the laborer is not only called upon to hold the hat in proper position and guide it between the rolls but also he must hold the hat back and this takes considerable strength as he must pull against the action of the machine. This retarding operation is useless and trying on the laborer, not only adding to his discomfort but ultimately decreasing his efficiency. Furthermore the usual function of such apparatus is to remove small particles of fur from the brim of the hat and these particles have a tendency to fly up and about the vicinity of the pouncing rolls. Many of these particles drop back upon the brim of the hat and many machines now in use, especially where sandpaper and brim travel in the same direction where they are in contact, tend to grind such particles back into the brim of the hat thus filling the surface thereof with very fine dust, resulting in an unattractive and inferior product. One of the objects of this invention is to provide apparatus which overcomes the above-mentioned difficulties as well as many others.

Referring now to Figure 1, a machine casing generally indicated at 10 supports a pair of drive shafts 11 and 12, shaft 12 being borne in a housing 10a projecting upwardly from the casing. The angle between the axes of shafts 11 and 12 is preferably acute to permit registry of the surfaces of a conical feed and support drum 13 and a conical pouncing drum 14, these drums being respectively mounted on shafts 11 and 12. Support and feed drum 13 is preferably covered with soft rubber 13a (Figure 2) and pouncing drum 14 (Figure 1) has an abrading surface such as a detachable piece of sandpaper 14a, these drums being operatively related to receive therebetween and pounce the brim of hat A. Surrounding substantially the upper portion of pouncing drum 14, I preferably provide an exhaust hood 55 (Figures 1 and 2) which receives and disposes of material abraded from the surface of the hat brim. To assist the feeding action of drum 13, I have provided an idler generally indicated at 15 (Figures 1 and 2) which forces the brim of the hat against the drum 13 in a manner to be described hereinafter.

More specifically, shaft 11 (Figure 1) is rotatably mounted in bearing portions 16a, 16b, and 16c of a bracket generally indicated at 16. A gear 17 is secured to shaft 11 and meshes with a relatively smaller gear 18 mounted on a shaft 20.

Gears 17 and 18 are preferably mounted in a gear casing 19 into which extends shaft 20, this shaft being driven by a motor 21 mounted in a motor housing 22. Motor housing 22 and gear casing 19 preferably are integral parts of bracket 16. Thus motor 21 drives shaft 11 and accordingly feed drum 13 at a speed lower than that of the motor's speed due to the reduction provided by gears 17 and 18.

Bracket 16 includes an arm or projection 23 which is pivotally mounted on a stud 24. A thrust collar 25 is mounted on shaft 11 adjacent drum 13 and is preferably connected to a foot pedal 26 by means of a link 27, foot pedal 26 being pivotally secured to a support 28. Accordingly, upon manipulation of foot pedal 26, bracket 16 and its contents, shaft 11 and drum 13 are pivoted about the axis of pin 24 to effect movement of feed drum 13 toward or away from pouncing drum 14, and this for the purpose of facilitating the placing of a hat brim between the drums, the removal of the hat brim therefrom, to enable varying operating pressures to be exerted on the hat brim at will, and to permit different feed rates of the hat brim.

Still referring to Figure 1, shaft 12 which drives pouncing drum 14 is driven by a motor 29 mounted within housing 10a and the axis of shaft 12 is preferably substantially horizontal. As above noted, drums 13 and 14 are preferably conical and to bring their surfaces into registry the axis of shaft 11 is inclined with respect to the axis of shaft 12. Under certain circumstances, it is desirable that drums 13 and 14 be replaced by corresponding drums but having larger or smaller mean diameters. To provide for the registry of the surfaces of such replacement drums, the angularity of the axis of shaft 11 is changed with respect to the axis of shaft 12; also the adjustability of shaft 11 makes possible the varying of the point of tangency between drums 13 and 14.

To this end, I have provided a substantially U-shaped bracket generally indicated at 30 through the legs 30a of which the reduced ends 24a (Figure 4) of pin 24 extend. The sides 10b and 10c (Figure 4) of casing 10 are slotted as at 34 (see also Figure 1) and these slots slidably receive reduced ends 24a of pin 24.

The cross piece 30b (Figure 1) of bracket 30 is suitably bored to receive rotatably a screw 31 which projects upwardly from bracket 30 and threadably engages and extends through a nut 32 secured to the top of casing 10. A pair of collars 35 and 36 are secured to screw 31 on opposite sides of cross piece 30b to rotatably secure screw 31 in assembled relation with bracket 30. The upper end of screw 31 has secured thereto a hand wheel 33 or the like and turning of this wheel in one direction or the other rotates screw 31 to raise or lower bracket 30 which, in turn, raises or lowers the assembly comprising bracket 16, shaft 11, and feed drum 13, thus changing the operative axis of the feed drums and bringing the surface thereof in registry with the surface of pouncing drum 14. It will be noted that the outer end of shaft 11 pivots about pin 27a which secures link 27 and collar 25 in pivotal relation. Accordingly, when the end of shaft 11, which is borne in bracket 16, is raised by manipulation of hand wheel 33, the end of the shaft on which feed drum 13 is mounted is lowered. Thus, it is possible to use feed and pouncing drums of practically any desired size. From this it follows that hat brims of practically any size may be pounced.

Idler 15 (Figure 3) preferably comprises a soft

rubber coating 37 mounted on a conical drum 38 having bores 39 and 40. A bell crank lever generally indicated at 41 (Figure 1) includes an arm 41a and an arm 41b. Arm 41a (Figure 3) is suitably bored to receive a spindle generally indicated at 42, this spindle being secured within arm 41a preferably by means of a set screw 43. Spindle 42 includes a conical portion 44 the end 45 of which is reduced. A pair of anti-friction bearings 46 and 47 are mounted respectively on reduced end 45 of spindle 42 and on the portion of the spindle adjacent conical portion 44. Bearings 46 and 47 are respectively received in bores 39 and 40 of conical roller 38 and these bearings in addition to spindle 42 are retained in assembled relation with roller 38 by means of a plug 48 screwed into a threaded portion of bore 40. As may be more clearly seen in Figure 1, bell crank lever 41 is pivotally mounted on a pin 49 which is secured to a boss or lug 50 projecting from housing 10a.

A tension spring 51 is secured at its opposite ends respectively to arm 41b of bell crank lever 41 and to a pin 52 projecting from casing 10. Spring 51 urges idler 15 downwardly against feed drum 13, the downward bias of the idler preferably being limited by a stop screw 53 threadably related to arm 41b of bell crank lever 41 and extending therethrough toward casing 10. Stop screw 53 may be adjusted to determine the extent of downward movement of idler 15 and a lock nut 54 maintains this adjustment. The downward movement of idler 15 is also controlled by the downward movement of feed drum 13 upon release of foot pedal 26. However, the distance of downward movement of feed drum 13 is controlled by a stop 28a on support 28 and this distance is preferably in excess of the extent of downward movement of idler 15. Accordingly, upon separation of drums 13 and 14 either to place a hat brim therebetween or remove a hat brim therefrom, feed drum 13 is out of contact with idler 15 and the hat accordingly can be easily handled.

It should also be noted that when drums 13 and 14 are replaced by drums having different mean diameters, it may be necessary also to replace idler 15. This change may be readily accomplished by loosening set screw 43 (Figure 3) and sliding the whole idler unit out of the bore 50 in arm 41a of bell crank lever 41.

As pointed out above, support and feed drum 13 is provided with a rubber surface 13a while pouncing drum 14 has a sandpaper cover 14a. The coefficients of friction of rubber and sandpaper, for example, are considerably different and this phenomenon is utilized in effecting the feed of the hat brim during the pouncing thereof.

With reference to Figure 2, it will be noted that while feed drum 13 and pouncing drum 14 both preferably revolve in a clockwise direction, as indicated by the arrows, the surfaces of each drum which contact opposite sides of the hat brim are moving in opposite directions. Furthermore, through the gear reduction provided by gears 17 and 18 (Figure 1), feed drum 13 (Figure 2) revolves at a substantially lower rate as, for example, 100 R. P. M. than pouncing drum 14 which rotates, for example, at 2500 R. P. M.

The superior friction of the soft rubber coating 13a on feed drum 13 (Figure 2) against the felt hat brim enables support and feed drum 13 to control the rate of feed of the brim under pouncing drum 14. The downward bias of idler 15 increases the adhesion of the hat brim to the

support drum thus making the driving effect thereof sufficiently strong to feed the hat brim uniformly against the retarding action of pouncing drum 14.

It is preferable that drums 13 and 14 rotate in the same direction rather than drum 13 rotating clockwise and pouncing drum 14 rotating counterclockwise. If pouncing drum 14 rotates counterclockwise, the hat brim becomes very dirty and this because a certain proportion of the felt cut off by the pouncing drum follows the drum around instead of being sucked into exhaust hood 55 and falls on the hat or adheres to the pouncing drum. This felt thence passes between the drums again and is reduced to still finer dust and rolled into the hat brim. By rotating pouncing drum 14 in clockwise direction, the material abraded from the brim surface which is not sucked through exhaust hood 55, falls on the processed portion of the brim which does not immediately again pass between the drums. Such loose material accordingly is not reduced to still finer dust and rolled into the hat brim but merely lies loosely thereon in such a manner that it may be readily brushed or blown off.

It should further be noted that clockwise rotation of pouncing drum 14, in addition to leaving the hat brim much cleaner, lays the nap thereof down in the same direction as the nap on the crown of the hat, does not distort the hat brim by unduly stretching it, and can be operated at a much higher speed than a pouncing drum which revolves in a counterclockwise direction. This effects more rapid and efficient brim pouncing. If pouncing drum 14 revolved in a counterclockwise direction, it would also assist the feeding action of feed drum 13 rather than retard such feeding action which, in turn, might necessitate passing the hat brim between the drums many more times than necessary when drum 14 revolves clockwise and which further might result in a non-uniform feed rate of the hat brim.

Preferably a hand rest and guard 56 (Figures 1 and 2) is positioned adjacent the surface of feed drum 13 (Figure 2) and is secured to housing 10a (Figure 1). The provision of hand rest and guard 56 enables the operator to rest his hand near the drums and permits accurate feeding of the hat brim between the drums while materially lessening the danger of injury to the operator's hands.

Accordingly it will be seen that I have provided a hat brim pouncing machine in which the several objects referred to hereinabove in addition to many others are achieved in a thoroughly practical and efficient manner.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a hat brim pouncing machine or the like, in combination, rotatable means adapted to support and feed the brim of a hat, rotatable means operatively related to said support means for pouncing said hat brim, an idler member, means urging said idler member toward said support means to force said hat brim thereagainst, means for changing the angle of the operative axis of said support means with respect to the axis of said pouncing means, and driving means for ro-

tating said support means and said pouncing means.

2. In a hat brim pouncing machine, in combination, a rotatable pouncing drum, a rotatable support and feed drum, said drums being adapted to receive a hat brim therebetween and to feed and pounce said brim, an idler member operatively related to said feed drum, means biasing said idler toward said feed drum and means positively limiting the bias of said idler member toward said feed drum whereby the bias of said idler member may be varied at will.

3. In a hat pouncing machine, in combination, a support, a pair of frusto-conical members rotatably mounted in said support, the surfaces of said members having different coefficients of friction, means for rotating said members, and a freely rotatable idler element rotatably associated with one of said members.

4. In a hat pouncing machine, in combination, a support, a pair of members rotatably mounted on said support, means for rotating said members, a freely rotatable idler element operatively associated with one of said members, and resilient means biasing said idler element toward one of said members.

5. In a hat pouncing machine, in combination, a casing, a shaft rotatably mounted in said casing, a pouncing drum mounted on said shaft, driving means disposed in said casing for rotating said shaft, a bracket movably disposed in said casing, a shaft journaled in said bracket, a pouncing drum mounted on said second-mentioned shaft adjacent said first-mentioned pouncing drum, and means in said bracket for rotating said second-mentioned shaft in the same direction of rotation with respect to said first-mentioned shaft and at a reduced speed with respect thereto.

6. In a hat pouncing machine, in combination, a casing, a shaft rotatably mounted in said casing, a pouncing drum mounted on said shaft, driving means disposed in said casing for rotating said shaft, a bracket movably disposed in said casing, a shaft journaled in said bracket, a pouncing drum mounted on said second-mentioned shaft adjacent said first-mentioned pouncing drum, means in said bracket for rotating said second-mentioned shaft in the same direction of rotation with respect to said first-mentioned shaft and at a reduced speed with respect thereto, and means for moving said bracket to vary at will the position of the axis of said second-mentioned shaft with respect to the axis of said first-mentioned shaft.

7. In a hat pouncing machine, in combination, a casing, a pair of pouncing members rotatably mounted in said casing, said members having their axes of rotation out of parallelism, and means in said casing for driving one of said pouncing members, said means including a motor and a train of reduction gears, said motor and said gears being vertically movable as a unit to vary at will the inclination of the axis of said last-mentioned pouncing member with respect to the axis of the other pouncing member.

8. In a hat pouncing machine, in combination, a pair of rolls adapted to receive therebetween and pounce the brim of a hat, means for positively driving said rolls, and an idler roll operatively associated with one of said rolls and adapted to force said hat brim against said roll to effect feeding of the hat brim, said idler roll being adapted to rotate only when in contact with said hat brim.

9. In a hat pouncing machine, in combination, a casing, a pair of pouncing members rotatably mounted in said casing and having non-parallel axes of rotation, a motor mounted on said casing for driving one of said members, a second motor mounted on said casing and oper-

atively connected to the other of said members, and means for varying at will the inclination of the axis of one of said members with respect to the axis of the other of said members.

BURLING D. WELLS.
